REEL AND METHOD OF FORMING IT

Paul S. McCann, La Grange, Ill., assignor to
Western Electric Company, Incorporated, New
York, N. Y., a corporation of New York

Application November 10, 1934, Serial No. 752,449

18 Claims. (Cl. 242—77)

This invention relates to reels and methods of forming them, and more particularly to metallic reels for supporting material such as lead covered cable and the like.

5 It is an object of the present invention to provide a strong, durable though light weight reel structure and a simple and economical method of forming it.

In accordance with one embodiment the invention 10 contemplates forming the heads of a reel from cylindrical tubular metal stock formed out of its normal shape to conform in cross-section to a rectangular shape tapered so that the rectangle progressively changes from a substantially square 15 cross-section at one end of the tube to an oblong rectangle at the other end of the tube to form spokes broader at the end thereof which is to be the inner end than at the outer end. The spokes thus formed are welded together along their corresponding sides to produce an annulus to which are secured annular reinforcing elements to provide a reel head.

A better understanding of the invention will be 20 had from the following detailed description when 25 considered in connection with the accompanying drawings, wherein

Fig. 1 is a side elevational view of a reel embodying the invention;

Fig. 2 is a perspective view of one of the spokes; 30 Fig. 3 is an enlarged fragmentary sectional view taken along the line 3—3 of Fig. 1 in the direction of the arrows;

Fig. 4 is a sectional view of an alternate embodiment of the invention when a straight type 35 of drum is used;

Fig. 5 is a view in perspective of a tube before the forming thereof with a set of forming mandrels which may be used, inserted part way into the tube;

40 Fig. 6 is a view in perspective showing the assembled position of the mandrels shown in Fig. 5, as they will be in the tube after the tube has been formed, and

Fig. 7 is a view showing how a flat rectangular 45 plate may be formed into a spoke in accordance with the invention.

Referring now to the drawings wherein like reference characters designate the same parts throughout the several views, a reel indicated 50 generally at 10 may be formed by welding together a plurality of spokes 11, and securing to the inner and outer surfaces of the spokes a pair of annular channel members 12 and 13, respectively, to form a reel head. In the preferred embodiment of the 55 invention the spokes 11 as shown in perspective

in Fig. 2 may be formed by either of two methods; one of the methods proposed is to take a cylindrical tube 14 of sheet metal (Fig. 5) and bend it to conform to the shape shown in Fig. 2 by inserting therein a three-part mandrel comprised 5 of a wedge 15 and a pair of forming tools 16 and 17. The forming tools 16 and 17 and wedge 15 may be pressed into the tube 14 until they assume the relative positions shown in Fig. 6 whereupon the tube will be formed to the shape shown in 10 Fig. 2. After a predetermined number of spokes 11 have been thus formed they may be welded 15 to each other and to a pair of annular channel members 12 and 13 (see Figs. 1 and 3) at the points of contact between the channel members 15 and the spokes.

After a number of spokes 11 have been welded together to form an annular disk, and the channel members 12 and 13 have been affixed thereto, a flanged drum 18 may be secured between a pair 20 of such heads by inserting through bolts 19 through apertures 20 and 21 in the flanges of the channel member 12 and through apertures 22 in the flange of the drum 18. The drum 18 is provided with an aperture 23 through which the inner 25 end of material to be wound upon the reel may be extended while the material is in position upon the reel.

When a reel such as that disclosed is being used, it is necessary to wind and unwind the material on the reel. Accordingly a spider 24 may be provided of the type disclosed in the patent to A. A. Bureau 1,911,427 which may be secured to the reel as disclosed in said patent.

Another embodiment of the invention contemplates the utilization of a straight or flangeless drum 25 (Fig. 4), and in this embodiment of the invention the reel head is made up in substantially the same manner as that disclosed hereinbefore; the tubular spokes 11 being of the same 40 construction and configuration as in the other embodiment of the invention and the annular channel member 13 is secured to the outer ends of the spokes 11 in the same manner as in the other embodiment, but an inner annular channel 45 member 26 is used in place of the channel member 12. It will be noted that the flanges of the channel member 26 extend outwardly, whereas the flanges of the channel member 12 extend inwardly. This construction is used so that the 50 straight drum 25 may be secured by bolts 27 to the channel member 26, suitable apertures 28 being provided in selected ones of the spokes 11 to permit the insertion of a tool to fasten the bolt 27.

With the type of drum last disclosed, a slightly different type of spider is necessary and a spider which may be used is shown in Fig. 4 wherein the arms of the spider have a flange 29 formed thereon through which the bolts 27 may be passed for securing the spider in place.

In Fig. 7 there is shown a sheet of metal 30 having dot and dash lines 31 thereon which indicate bending lines. If the flat rectangular sheet 30 is bent upon a brake press with a series of right angle bends all made in the same direction along the bent lines 31, a tubular spoke such as that shown in Fig. 2 may be formed, and will be identical with the spoke formed from cylindrical tube 14, with the exception that as shown in Fig. 2 there will be either a crack or a seam along the dot and dash line 32. Spokes formed in the manner just disclosed may be welded together to form an annular disk to be used as a reel head in identically the same manner as the tubular spokes formed from a cylindrical tube.

Although specific embodiments of the invention have been disclosed, it will be apparent that the invention is subject to alterations without departing from the scope of the appended claims.

What is claimed is:

1. A reel head comprising a plurality of tubular tapered spokes secured directly each to another in abutting relation to form a body having a substantially circular outer periphery.

2. The method of forming a reel comprising forming rectangular tubes with constant perimeters and with the width thereof varying as a function of the depth thereof, securing a series of such tubes together to form a pair of annuli, securing annular members to the inner and outer surfaces of the annuli formed by the tubes, and positioning a drum between said annuli.

3. The method of forming a reel head which comprises forming a plurality of tubular members with a rectangular cross section of a predetermined constant perimeter throughout their length but with progressively changing side dimensions to form spokes which when welded together will form an annulus, securing a plurality of said spokes together at adjacent sides to form an annulus, and securing supporting members to the inner and outer ends of said spokes.

4. A reel comprising spaced heads and a drum, each of said heads comprising a plurality of spokes secured together to form an annulus and each spoke having a rectangular cross-section of constant perimeter throughout its length and being broader at its inner end than at its outer end and being wider at its outer end than at its inner end, and reinforcing members secured to the inner and outer surfaces of said annulus.

5. The method of forming reel heads which comprises forming cylindrical tubular stock to the shape of a rectangular tube having a constant perimeter the width thereof varying as a function of the depth thereof to taper the outer end of the tube in one plane and to taper the inner end thereof in another plane, and securing a plurality of said rectangular tubes together to form an annulus.

6. A reel head comprising a plurality of hollow spokes having a rectangular cross-section secured together to form an annulus with flat surfaces of the spokes in abutting relation, said abutting surfaces lying in planes perpendicular to the reel head surface, and inner and outer reinforcing members secured to the inner and outer surfaces of the reel head.

7. The method of forming a reel head which

comprises forming a plurality of hollow spokes with a rectangular cross-section and tapering side walls, and securing said hollow spokes together with corresponding side walls in abutting relation.

8. The method of forming a reel head which comprises forming a plurality of hollow spokes with a rectangular cross-section and tapering side walls, securing said hollow spokes together with corresponding side walls in abutting relation to 10 form an annulus, and securing reinforcing members to the inner and outer surfaces of the annulus.

9. The method of forming reel heads which comprises forming spokes with a rectangular cross-section and a constant perimeter throughout their length but with adjoining sides tapered in opposite directions, and assembling a plurality of such spokes with corresponding surfaces in abutting relation to form an annulus. 20

10. The method of forming reel heads which comprises forming spokes with a rectangular cross-section and a constant perimeter throughout their length but with adjoining sides tapered in opposite directions, assembling a plurality of 25 such spokes with corresponding surfaces in abutting relation to form an annulus, and securing reinforcing members to the inner and outer edges of the annulus.

11. A reel head comprised of a plurality of hollow rectangular spokes having a constant perimeter throughout their length but with adjoining sides tapered in opposite directions and assembled to form an annulus, and a pair of reinforcing annular channel members secured to the inner and outer edges of the annulus. 30

12. A reel head comprised of a plurality of hollow rectangular spokes having a constant perimeter throughout their length but with adjoining sides tapered in opposite directions and assembled to form an annulus, and a pair of reinforcing annular channel members secured to the inner and outer edges of the annulus with their flanges extending toward the center of the annulus. 40

13. A reel comprised of spaced heads and a flanged drum, said heads each comprised of a plurality of hollow rectangular spokes having a constant perimeter throughout their length but with adjoining sides tapered in opposite directions and assembled to form an annulus, a pair of reinforcing annular channel members secured to the inner and outer edges of the annulus, and means for supporting said drum between said heads. 45

14. A reel comprising spaced heads and a drum, each of said heads comprising a plurality of spokes secured together to form an annulus and each spoke having a rectangular cross-section of constant perimeter throughout its length and being broader at its inner end than at its outer end and being wider at its outer end than at its inner end, reinforcing members secured to the inner and outer surfaces of said annulus, and means for securing the drum between said heads. 50

15. A method of forming reel heads comprising forming cylindrical tubular members to tubes each having a rectangular cross-section throughout its length with the sides in parallel planes tapered in one direction and the sides at right angles thereto tapered in the opposite direction, and assembling a plurality of said tubes to form an annulus with corresponding surfaces in abutting relation. 60

16. A method of forming reel heads compris-

ing bending rectangular sheets of material to form tubes each having a rectangular cross-section throughout its length with the sides in parallel planes tapered in one direction and the sides at right angles thereto tapered in the opposite direction, and assembling a plurality of said tubes to form an annulus with corresponding surfaces in abutting relation.

17. A spoke for reel heads and the like comprising a sheet metal tube tapered from end to end in one plane and tapered in the opposite di-

rection in a plane at right angles to said first plane.

18. A spoke for reel heads and the like comprising a sheet metal tube having a substantially rectangular cross-section of substantially constant periphery throughout its length and being tapered toward its inner end in one plane and tapered toward its outer end in a plane at right angles to said first plane.

PAUL S. McCANN.
